UNITED STATES PATENT OFFICE.

FORD L. SABIN, OF CLEVELAND HEIGHTS, OHIO, ASSIGNOR TO THE WELLMAN-SEAVER-MORGAN COMPANY, OF CLEVELAND, OHIO, A CORPORATION OF OHIO.

DOCK-CRANE.

1,378,981.

Specification of Letters Patent.

Patented May 24, 1921.

Application filed October 24, 1919. Serial No. 332,967.

To all whom it may concern:

Be it known that I, FORD L. SABIN, a citizen of the United States, residing at Cleveland Heights, in the county of Cuyahoga and State of Ohio, have invented a certain new and useful Improvement in Dock-Cranes, of which the following is a full, clear, and exact description.

This invention relates to an improved dock crane of a type which is designed to be run along or to be positioned at any point on a dock, and having a boom whose outer end is intended to project over a boat to be loaded or unloaded, and whose inner end is adapted to project into a dock shed so that by means of a trolley movable along the boom, merchandise may be transferred from the vessel to the shed, or vice versa.

The principal object of the invention is to provide a construction by which the outer part of the boom can be elevated and swung clear of the boat rigging, and the inner end of the boom may at the same time be moved outwardly so as to clear the uprights of the shed, thus allowing the crane as a whole to be moved along the dock.

In the embodiment of my invention herein illustrated a boom composed of two hinged parts is utilized, and provision is made for moving the inner portion of the boom in an endwise direction along a suitable trackway of the crane structure while the outer part of the boom is adapted to be swung vertically. The construction is such that when it is desired to move the crane along the dock, the inner section of the boom is moved outwardly so as to clear the shed and at the same time, through the power which imparts endwise movement to the inner section, the outer section is swung upwardly.

The invention may be further briefly summarized as consisting in certain novel details of construction and combinations and arrangements of parts which will be described in the specification and set forth in the appended claims.

In the accompanying sheet of drawings, wherein I have shown the preferred embodiment of the invention, Figure 1 is a side view of a crane embodying my invention with the dock and other parts with which

the crane is utilized being shown in section or end elevation. Fig. 2 is an enlarged longitudinal sectional view taken through the boom when the latter is in a position permitting the crane to be moved along the dock; Fig. 3 is a transverse sectional view through a portion of the crane structure showing also the trolley which is adapted to be moved along the boom, and Fig. 4 is a top plan view of a portion of the boom and a portion of the crane structure which supports the same.

Referring now to the drawings, 10 represents the dock, 11 represents the dock shed in which the merchandise is stored when delivered from a boat 12. Adapted to travel along the dock at the front of the shed 11 is a crane structure 13 which in this instance runs along the lower rail 14 and an upper rail 15 carried by the dock shed. Merchandise is adapted to be transferred from the boat to the shed, or from the shed to the boat by a trolley, indicated at 16 adapted to travel along a boom 17 which when in position for transferring the merchandise is preferably inclined substantially as shown in Fig. 1, and has its outer end extending over the boat and its inner end 80 extending into the dock shed. It will be seen therefore that to permit the crane to be transferred along the dock, the outer end of the boom must be raised so as to clear the boat rigging and the inner end of the 85 boom must be moved outwardly so as to clear the uprights at the front of the dock shed. It is important also that when the boom is shifted to permit the crane to be moved, the inner end of the boom be given 90 such a movement that it will not strike or interfere with cars, such as shown at 18, which may be on tracks between the dock shed and the edge of the dock.

To accomplish this result it has heretofore 95 been proposed to pivot the boom on the crane structure for movement about a transverse axis the pivot point being at some point between the ends of the boom, and it has been proposed also to first shift the entire boom in an endwise direction in the crane structure, and then to swing it about a transverse axis.

The arrangement or structure contem-

plated by the present invention accomplishes the desired results in a simple but very effective manner.

In carrying out my invention, the boom 17 is formed of two parts 17^a, 17^b, which are hinged one on the other, the parts being connected by a transverse pivot indicated by 19, so that the outer section 17^a may be swung on the forward end of the inner section 17^b. Additionally, I provide in the crane structure trackways 20, 20, along which the inner section 17^b of the boom is adapted to travel in an endwise direction. In this instance the trackways are formed by pairs of oppositely disposed rails 20^a, 20^b, which rails are positioned in the crane structure a suitable distance apart on the opposite sides of the longitudinal axis of the boom.

20 In this case the two trackways on opposite sides of the boom axis are spaced a distance apart which is considerably wider than the boom proper, and the inner section 17^b of the boom is provided with a laterally extending portion 21 at the sides of which are track wheels 22 which engage the rails forming the trackways. Preferably the trackways are inclined as shown on Figs. 1 and 2, so that when the boom is in operative position with the forward section 17^a in alinement with the rear section 17^b, the boom will be inclined as previously stated. This facilitates the transporting of merchandise from the boat to the dock, since 35 the trolley can be run down the boom by gravity. A further advantage of the inclined normal position of the boom lies in the fact that the boom can be restored to its normal position by gravity.

40 In order that the axial movement of the rear section and the swinging movement of the forward section of the boom may take place simultaneously, through power applied at one point, the forward section of 45 the boom is connected to the top of the crane structure by a more or less rigid arm or rod 23. This rod is pivoted at one end to the boom section at 23^a, and is pivoted to the top of the frame structure at 23^b. By reason of this construction the outward endwise movement of the rear boom section is accompanied by an upward swinging of the outer boom section, and the inward endwise movement of the inner boom section is 55 accompanied by the downward swinging movement of the outer boom section, until both boom sections are in direct alinement.

The boom can be shifted in the manner just stated in different ways, but in this instance by a cable 24 adapted to be wound onto and unwound from a drum 25 located in the operator's station 26 on the crane structure. In this instance both ends of the cable pass about the drum and from the 60 drum, both portions of the cable pass for-

wardly about a pair of sheaves 27, which are supported on the crane structure (see Fig. 4). Then both portions of the cable pass rearwardly to and around a pair of sheaves 28 carried by the boom, then they 70 pass forwardly around a pair of sheaves 29 arranged coaxially with respect to the sheaves 27; then again rearwardly and around a horizontal sheave 30, likewise carried by the boom structure. With this arrangement by winding in on the cable the inner or rear section of the boom is pulled outwardly along the trackways, this movement being accompanied by the upward swinging movement of the outer boom section. And when the cable is paid out the boom section 17^a runs down the trackways to its normal position, where a stop is encountered which limits its inward movement, this inward movement of the boom 80 section 17^a being accompanied by the downward swinging of the outer boom section.

It might be mentioned that in Fig. 1 the boom is in its normal position, and that in Figs. 2 and 4 the boom or so much of it as 90 is shown in these figures is in its abnormal position which permits the crane as a whole to be transported along the dock. It will be noted also by reference to Fig. 2 that when the boom has been given its full movement 95 from normal to abnormal position the forward end of the inner boom section 17^a is at the front of the crane structure 13, the forward part of wheels 22 which travel along the trackways of the boom structure then 100 being at the extreme forward ends of the trackways. Likewise when the boom is in the position stated the forward section 17^a is nearly vertical.

In conclusion, it might be stated that any 105 suitable form of trolley may be employed, the trolley and its operating mechanism being immaterial to my invention. It will be sufficient to state that the trolley 16 heretofore referred to will have suitable track 110 wheels 16^a designed to travel along two rails 31 of the boom, as shown in Fig. 3, which rails are of course carried part by the endwise movable section 17^a and part by the 115 swinging boom section 17^b, the joint occurring in the trolley rails at the joint or pivot point of the two boom sections. It is important that when the two boom sections are 120 in alinement ready for use, the portions of the trolley rails carried by the two boom sections be in alinement or sufficiently close alinement that the trolley can readily pass over the rail joints. The trolley is moved along the boom and trolley hook or load carrying device is raised and lowered by cables 125 32 and 33 which pass about suitable drums 34 and 35 in the operator's shed 26, these drums, as well as the boom shifting drum being all motor operated in any suitable manner.

I do not desire to be confined to the exact detail shown but aim in my claims to cover all modifications which do not involve a departure from the spirit and scope of my invention in its broadest aspects.

Having described my invention, I claim—

1. A dock crane comprising a crane structure having a boom for a trolley, the boom being composed of relatively movable sections along both of which the trolley is adapted to travel, one section mounted for endwise movement in the crane structure.

10 2. A dock crane comprising a crane structure having a boom for a trolley, the boom being composed of hinged or pivoted sections along both of which the trolley is adapted to travel, one section mounted for endwise movement in the crane structure.

15 3. A dock crane comprising a crane structure having a boom for a trolley, the boom being composed of an inner section mounted for endwise movement in the crane structure, and an outer section hinged to the inner section to swing vertically, said trolley adapted 20 to travel along both sections.

25 4. A dock crane comprising a crane structure having a boom for a trolley, the crane structure having a trackway and the boom being composed of sections, one adapted to be shifted in an endwise direction along said trackway, and the other to be swung vertically relative to the crane structure, said trolley adapted to travel along both sections.

5. A dock crane comprising a crane structure having a boom for a trolley, the boom being composed of an endwise movable inner portion and a vertically swinging outer portion pivotally connected to the inner portion and having a connection with the frame such that when the inner portion is moved 35 endwise, the outer portion is swung on its pivot.

6. A dock crane comprising a crane structure having a boom for a trolley, said boom being composed of an endwise movable inner 40 section and a vertically swinging outer section pivoted to the inner section, means for moving said inner section in an endwise direction, and means for simultaneously causing the outer section to be swung on its 45 pivot.

7. A dock crane comprising a crane structure having a boom for a trolley, said boom being composed of an endwise movable inner portion and a vertically swinging outer portion pivoted to the end of the inner portion, power means connected to the inner portion 50 for moving it endwise, and means connecting the outer portion to the crane structure so that the said outer portion is swung vertically when the inner section is moved in an endwise direction by said power means.

In testimony whereof I hereunto affix my signature.

FORD L. SABIN.
